No. 833,140.

PATENTED OCT. 9, 1906.

J. A. STOWE.
CAR BRAKE.
APPLICATION FILED JAN. 8, 1906.

UNITED STATES PATENT OFFICE.

JOSEPH ALBERT STOWE, OF ARLINGTON, NEW JERSEY, ASSIGNOR TO
STERLING-MEAKER COMPANY, OF NEWARK, NEW JERSEY, A COR-
PORATION OF NEW JERSEY.

CAR-BRAKE.

No. 833,140.

Specification of Letters Patent.

Patented Oct. 9, 1906.

Application filed January 8, 1906. Serial No. 295,124.

To all whom it may concern:

Be it known that I, JOSEPH ALBERT STOWE, a citizen of the United States of America, and a resident of Arlington, in the State of New Jersey, have invented a new and useful Improvement in Car-Brakes, of which the following is a specification.

This invention relates to geared "staff-brakes" for the cars of electric railways and other street-railways; and it consists in certain novel combinations of parts hereinafter set forth and claimed.

The general objects of the invention are the multiplication of power to a sufficient extent, extreme simplicity of construction, a perfect coördination of parts, quick action, great strength, and the adaptation of the gearing and drum to be perfectly lubricated and kept free from dust.

The objects of the present invention, more particularly stated, are to provide for strongly attaching the brake-chain at the periphery of the drum and to provide for quick action on cars the brake-rigging of which is kept loose by a peculiarly constructed peripheral "extension" or peripheral enlargement on the drum, upon the outer extremity of which the brake-chain is so fastened, and for insuring the coiling of the chain around the drum beneath such enlargement in regular coils.

A sheet of drawings accompanies this specification as part thereof.

Figure 1 is a top view with the brake-staff in cross-section. Fig. 2 is a sectional side elevation projected from Fig. 1, showing additionally the parts at and above the platform. Fig. 3 is a side view of the gearing-inclosing housing or box detached. Figs. 4 and 5 are side views, respectively, of the pinion and the combined gear and drum removed from said box; and Fig. 6 is a bottom view of the combined gear and drum projected from Fig. 5.

Like reference characters refer to like parts in all the figures.

The improved brake device includes a box *a*, that may be and preferably is made of malleable iron in a single casting (shown detached by Fig. 3) and attached in customary manner to the bottom of the car-platform, as

in Fig. 2, by vertical bolts. The front end 1 of this box is closed and its interior is adapted to accommodate the pinion *b* of the power-multiplying gearing, (shown detached by Fig. 4,) with its angular bore 2 in position to receive the square at the lower end of the customary vertical staff *c*, bearings 3 and 4 for rounded portions of the staff being provided in the top and bottom of the box. The open rear end 5 of the box is widened and deepened to accommodate within it a combined gear and drum *d* (shown detached by Figs. 5 and 6) and is provided at top and bottom with sockets 6 and 7 for a vertical spindle *e*, upon which said combined gear and drum *d* rotates. Cotter-pins 8 and 9, extending through the lower ends of the staff *c* and spindle *e*, secure them against vertical displacement. It will be seen that provision is thus made for readily inserting the power-multiplying gearing and the chain-drum within a one-part housing-box and for removing them therefrom as required.

To provide for lubricating the spindle *e* and excluding dust therefrom, the spindle is made of steel grooved longitudinally to carry the lubricant downward, and the combined gear and drum *d* is chambered, as shown in Fig. 2, so that the spindle *e* is surrounded by an oil-chamber 10. A hole 11 is cut through the platform *f* to communicate with the upper end of the spindle *e* and is closed at top by a hinged cover 12, attached to a plate let into the platform in a customary way. This hole 11 is filled with waste, and plenty of oil is then poured in, and the spindle thus becomes well lubricated, while dust is effectively excluded therefrom both at top and bottom. A perfect "release" to free the wheels of the car is thus insured.

The hole 13, Fig. 2, in the platform *f*, which accommodates the staff *c*, is closed at top by a collar 14, surrounding the staff and projecting into the hole, the same being let into the platform so as to be flush with it and forming a rest for the staff-ratchet 15.

The combined gear and drum *d* (shown detached by Figs. 5 and 6) consists, in common with the pinion *b*, of a single casting, which may be of gray or gun iron. Immediately beneath the gear-disk 16, which is of the re-

quired diameter to interact with the pinion *b* and is located at the top, the periphery of the drum portion 17 is constructed with a peculiarly-shaped peripheral extension or enlargement 18, projecting practically to the full diameter of the gear at one point, as best seen in Fig. 6 and in dotted lines in Fig. 1, and including at that point an apertured radial wall 19, connecting the lower side of the gear-disk 16 to a guard flange or lip 20 nearly parallel therewith, extending around a portion 21 of said enlargement 18, which enlarges the effective periphery of the drum and is so located that when the chain *h* is wound on the drum to take up slack it will be kept by said lip 20 in contact with said portion 21 until the function of said portion 21 is accomplished. The remainder of said enlargement 18 forms an incline 22, by which the second coil of the chain *h* around the drum is compelled to take a position in contact with the smaller diameter of the drum beneath said lip 20 and incline 22 and below the first coil. The lower part of the drum, of said smaller diameter, extends downward to a sufficient extent and may be cylindrical, as shown. Said lip 20 on the chain-drum carries even a very slack chain into the space arranged for it above said lip and prevents the slack chain from falling around the lower part of the drum, and thus causing later coils to pile up over it. An eyebolt *i* extends through said radial wall 19 immediately beneath the gear-disk 16 and attaches to the combined gear and drum *d* the brake-chain *h*, which is preferably of the "twisted" form, (represented in Figs. 1 and 2,) so as to be wound on the drum in contiguous coils and so as to possess a limited amount of tensile elasticity. The other end of the chain *h* interacts with the customary hook-rod *k*, connected with the brake-levers of the car.

For roads on which the brake-rigging is kept taut with a minimum of lost motion the brake may be made without the peripheral enlargement of the drum, and other like modifications will suggest themselves to those skilled in the art.

Having thus described said improvement, I claim as my invention and desire to patent under this specification—

1. The combination, in a geared staff-brake for cars, of a combined gear and drum constructed with its gear-disk at top and with a peripheral enlargement of the drum portion beneath said gear-disk including a radial portion to which the chain is attached, an eyebolt extending lengthwise through said radial portion, and a brake-chain attached by means of said eyebolt.

2. The combination, in a geared staff-brake for cars, of a pinion interacting with the lower end of the staff in customary manner, a combined gear and drum constructed

with its gear-disk at top and with a peripheral enlargement of the drum portion beneath said gear-disk including a radial portion to which the chain is attached, an eyebolt extending lengthwise through said radial portion, and a brake-chain attached by means of said eyebolt.

3. The combination, in a geared staff-brake for cars, of a pinion interacting with the lower end of the staff in customary manner, a combined gear and drum constructed with its gear-disk at top and with a peripheral enlargement of the drum portion immediately beneath said gear-disk including a radial portion to which the chain is attached, a chain-supporting lip extending from said radial portion partly around the circumference of the drum, an enlargement of the effective periphery of the drum-body extending from the back of said radial portion partly around the circumference of the drum between said lip and said disk, and a smaller drum part extending downwardly beneath said lip, an eyebolt extending lengthwise through said radial portion, and a brake-chain attached by means of said eye-bolt.

4. The combination, in a geared staff-brake for cars, of a pinion interacting with the lower end of the staff in customary manner, a combined gear and drum constructed with its gear-disk at top and with a peripheral enlargement of the drum portion beneath said gear-disk including a radial portion to which the chain is attached, a chain-supporting lip extending from said radial portion partly around the circumference of the drum, an enlargement of the effective periphery of the drum-body extending from the back of said radial portion partly around the circumference of the drum between said lip and said disk, a circumferential incline on the opposite side of the drum portion in the same plane as the enlargement last named, the lower surface of said incline extending downward from the gear-disk to the plane of said lip, a smaller drum part extending downward beneath said lip and said incline, a brake-chain, and means for attaching the chain to said radial portion.

5. The combination, in a geared staff-brake for cars, of a pinion interacting with the lower end of the staff in customary manner, a combined gear and drum constructed with its gear-disk at top and with a peripheral enlargement of the drum portion immediately beneath said gear-disk including a radial portion to which the chain is attached, a chain-supporting lip extending from said radial portion partly around the circumference of the drum, an enlargement of the effective periphery of the drum-body extending from the back of said radial portion partly around the circumference of the drum

between said disk and said lip, a circumferential incline on the opposite side of the drum portion the lower surface of which extends downward from the gear-disk to the 5 plane of said lip, and a smaller drum part extending downward beneath said lip and said incline, an eyebolt extending endwise through

said radial portion, and a brake-chain attached by means of said eyebolt, substantially as hereinbefore specified.
